US00D996210S

(12) **United States Design Patent** (10) **Patent No.:** **US D996,210 S**
(45) **Date of Patent:** **** Aug. 22, 2023**

(54) **CAP WITH PLUG SEAL**

(71) Applicant: **INTEGRATED LINER TECHNOLOGIES, INC.**, Rensselaer, NY (US)

(72) Inventors: **Lenny Diaz**, Clifton Park, NY (US); **Paul M. Petrosino**, Schoharie, NY (US)

(73) Assignee: **INTEGRATED LINER TECHNOLOGIES, INC.**, Rensselaer, NY (US)

(**) Term: **15 Years**

(21) Appl. No.: **29/831,820**

(22) Filed: **Mar. 23, 2022**

Related U.S. Application Data

(62) Division of application No. 29/652,758, filed on Nov. 13, 2020, now Pat. No. Des. 947,025.

(57) **CLAIM**

The ornamental design for a cap with plug seal, as shown and described.

DESCRIPTION

FIG. 1 is a top side perspective view of a cap with plug seal, showing our new design;

FIG. 2 is an exploded top side perspective view thereof;

FIG. 3 is a front side view of the plug seal separated from the cap thereof;

FIG. 4 is a front side cross sectional view of the plug seal separated from the cap thereof, taken in the direction of line 4-4 on FIG. 2;

FIG. 5 is a top plan view thereof;

FIG. 6 is a bottom plan view thereof;

FIG. 7 is a front side view thereof;

FIG. 8 is a back side view thereof;

FIG. 9 is a left side view thereof;

FIG. 10 is a right side view thereof; and,

FIG. 11 is a top side perspective view thereof in a position of use with an exemplary vial.

The broken lines are shown for the purpose of illustrating parts of the article as well as environmental subject matter of an exemplary vial. None of the broken lines form part of the claimed design.

1 Claim, 8 Drawing Sheets
